EDWARD BLOOM, OF PATERSON, NEW JERSEY.

CONTROL DEVICE FOR WARPING-MACHINES.

1,212,604.

Specification of Letters Patent. Patented Jan. 16, 1917.

Original application filed March 21, 1914, Serial No. 826,142. Divided and this application filed April 30, 1915. Serial No. 24,883.

To all whom it may concern:

Be it known that I, EDWARD BLOOM, a citizen of the United States, residing at Paterson, in the county of Passaic and State of New Jersey, have invented certain new and useful Improvements in Control Devices for Warping-Machines, of which the following is a specification.

This application is a division of my application for patent for improvements in warping machines, filed March 21st, 1914, Serial No. 826142.

This invention relates to warping machines, and it has for its principal object to provide a warping machine with a simple and reliable means for stopping the rotation of the reel when a predetermined length of warp has been wound on the reel.

According to this invention the reel-driving mechanism includes a disconective clutch-connection whose movable clutch member is controlled by a shiftable power-transmitting means which is moved from the reel in the direction to shift said member for breaking the clutch-connection and which is provided with a normally active detent which, on said movement of said means, locks the latter against return, leaving the power cut off until the operator reestablishes it; preferably the mechanism for actuating said means is a pattern mechanism having a disconective connection with the reel (whereby it is driven) so that on disestablishing said connection the pattern mechanism may be moved to allow reestablishing the aforesaid clutch-connection on releasing the detent, and also to reset the pattern mechanism, all without disturbing the reel.

In the accompanying drawing, Figure 1 is a front elevation of so much of the machine as directly includes said improvements; and, Fig. 2 is a plan view of the improvements.

The frame *a*, reel shaft *c* journaled in the frame in the usual manner, the reel-driving band or hoop *d*, the rotary shaft *e* carrying a friction wheel *f* to engage the band *d* and so drive the reel, the lever *g* in which said shaft is journaled and the lever *h* operated from suitable means, such as a treadle (not shown), so as to effect movement of lever *g* up and down to shift the friction wheel *f* into and out of contact with the band *d*, are or may be all substantially the same as in any warping machine of the

type of that herein shown, to wit, a horizontal warping machine. In the present instance, the pulley *i* rotated by suitable means (not shown) is freely revoluble on the shaft *e* and forms one member of a clutch, of which the other member is the part marked *k* in Fig. 1, being splined on said shaft. On shifting this member to the left in Fig. 1 the power is transmitted from *i* to *e*; when shifted to the right, *i* rotates idly.

In a bracket *l* projecting from the frame is fulcrumed a lever *m* having a fork *n* engaged in the peripherally grooved collar *o* of the clutch member *k* and being normally influenced by a spring *p* to maintain clutch member *k* engaged with the other clutch member—pulley *i*. Pivoted to one arm of this lever, which overhangs a part of the frame *a*, is a pendent detent *m'*.

In brackets *q* secured to the frame above the pulley shaft *e* is arranged the shaft *r* affording a fulcrum for four levers, one of which, *s*, is connected with the lever *m* by the rod *t*. In these brackets is journaled a shaft *u* having a handle *v* at one end whereby it may be manually rotated and carrying a sprocket wheel *w* over which extends an endless pattern chain *x*, provided with (in the present instance) four balls *y*. The lever *s* rests on this pattern chain in vertical alinement with one of these balls, so that, as the chain is advanced once in each circuit thereof the lever is elevated.

The shaft *u* carries a fixed clutch member *z* and on it is splined a movable clutch member *2* having a worm-wheel *3* meshing with the worm *4* on the shaft *c* of the reel. For moving the clutch member *2* I provide the sliding fork *5* arranged on the shaft *r* and engaged in the groove *6* of said clutch member, said fork being normally forced to the right in Fig. 1 by a spring *7* coiled between the fork and the left-hand bracket *2* and thereby maintaining the disconective connection *z*—*2* normally established. *8* is a set screw for securing the fork in a position where said connection *z*—*2* is disestablished. The other three levers (9) in the group including the levers *s* are vertically alined with and adapted to be actuated by the three remaining balls on the chain *x*. When actuated, they actuate an alarm through instrumentalities not herein material and fully set forth in my application referred to.

Operation: In the winding of each section or other length of warp on the reel the alarm device is actuated three times (in the present instance), first to notify the attendant 5 when to insert the first lease cord, next to notify when to insert the second lease cord and finally to signal the approach of the point in the section where it should be cut off; thereupon the reel is automatically 10 brought to a standstill. These operations are performed by the levers 9 and s in the order of their arrangement, from right to left in Fig. 1, as they are successively lifted by the balls on the pattern chain. The reel, upon 15 being brought to a stop by the elevation of lever s, is maintained at a standstill by the detent m' which, on the movement of lever m to shift clutch member k out of clutching engagement with pulley i, seats upon the 20 frame and thus prevents return movement of said lever and the clutch member. Having cut off and tied the section thus wound on the reel and attached the end of the new section to the reel, the attendant employs 25 fork 5 to disestablish the connection z-2, whereupon handle v is turned to shift the pattern chain forwardly just enough to clear the ball which stopped the machine from beneath the lever s. Detent m' is then moved 30 out of engagement with the frame, allowing the lever m and consequently the clutch-member k to return to their normal positions, whereby the reel is again put in motion.

Having thus fully described my invention, what I claim as new and desire to secure by Letters Patent is:—

1. A warping machine including, in combination, a frame, a reel journaled therein, 40 means to rotate the reel including clutch members forming a clutch connection and one being withdrawable out of clutching engagement with the other, and means, including a repeating mechanism, for transmitting 45 withdrawing motion from the reel to the first-named clutch member.

2. A warping machine including, in combination, a frame, a reel journaled therein, means to rotate the reel including clutch

members forming a clutch connection and 50 one being withdrawable out of clutching engagement with the other, and means including a disconnective clutch connection for transmitting withdrawing motion from the reel to said first-named member. 55

3. A warping machine including, in combination, a frame, a reel journaled therein, means to rotate the reel including clutch members forming a clutch connection and one being withdrawable out of engagement 60 with the other, and means, including a disconnective clutch connection and a repeating mechanism, for transmitting withdrawing motion from the reel to said first-named member. 65

4. A warping machine including, in combination, a frame, a reel shaft journaled therein, a reel carried by said shaft, a repeating mechanism operatively connected with and driven by the reel shaft, a lever 70 engaged with the repeating mechanism, means to rotate the reel including clutch members forming a clutch connection and one being withdrawable out of clutching engagement with the other, another lever fulcrumed in the frame and engaged with the first-named clutch member, and a link connecting said levers. 75

5. A warping machine including, in combination, a frame, a reel journaled therein, 80 means to rotate the reel including clutch members forming a clutch connection and one being withdrawable out of clutching engagement with the other, means for transmitting withdrawing motion from the reel 85 to the first-named member, including a repeating mechanism, disconnective power-transmitting mechanism connecting the repeating mechanism and reel, back and forth moving means actuated by the pattern-mechanism and operatively connected with the first-named clutch member, and a detent 90 normally active to lock the last-named means against return upon movement in one direction. 95

In testimony whereof I affix my signature.

EDWARD BLOOM.
